UNITED STATES PATENT OFFICE.

HARRY E. KADEN, OF CLEVELAND, OHIO, ASSIGNOR TO THE ART SPECIALTY COMPANY, OF CLEVELAND, OHIO, A CORPORATION OF OHIO.

FIXTURE ELEMENT.

Application filed November 26, 1926. Serial No. 150,844.

This invention relates to improvements in the frame construction of lighting fixtures, particularly of the style known as lanterns that are used extensively on porches, or in 5 halls or dens, the invention having to do more especially with a unique form of element or member for use in such frames, and with the method of producing the same.

Reference is here made to the accompanying drawings wherein embodiments of the invention are illustrated. Fig. 1 is a side elevation, and Fig. 2 a plan view, of a lighting fixture incorporating my improvements; Fig. 3 is a section on the line 3—3 of Fig. 1; Fig. 4 a section on the line 4—4 of Fig. 3; Fig. 5 is a perspective view of a strip of material, cut of a length to make one of the elements or members of the fixture frame and given its initial angular form; Fig. 6 is a 20 plan view of the same strip, notched preparatory to bending; Figs. 7, 8 and 9 are plan views, respectively of a square, a triangular, and a hexagonal fixture constructed in accordance with my invention; and Figs. 7^a, 8^a 25 and 9^a are plans of the formed and notched strips from which the top members of the fixture frames shown, respectively, in Figs. 7, 8 and 9, are made.

Fixture frames comprised of polygonal top 30 and bottom members or elements that are angular in cross section, and whose corresponding corners are connected together by angular uprights forming panels that are filled by glass panes, are old.

Heretofore the top and bottom polygonal members have each been constructed of separate pieces that constitute its respective sides or faces, and these pieces have been connected together at the corners of the member 35 by miter joints. This method of construction was rendered tedious by the necessity of handling so many separate pieces and required very exacting and careful work in the joining of the pieces together in order to produce a member that would be regular of outline and neat of appearance. Production was thus retarded and consequently rendered expensive.

It is the purpose of my invention to greatly 50 improve and to cheapen the construction and method of manufacture of lighting fixtures of the aforesaid style by forming each top and bottom member or element of a single strip of material, such as sheet metal of proper gauge and quality and notching the same

prior to bending in such a way that accuracy and regularity of design is assured when the strip is bent into final shape.

Referring to the parts by reference characters, 1 designates, generally, the top member and 2 the bottom member of the fixture frame which, as illustrated in Figs. 1 to 4, are hexagonal in plan. The member 1 is formed from a strip of material that is bent, by suitable means, into angular cross section thereby to effect flanges 3 and 4, as shown in the perspective view of Fig. 5. After the strip has been so formed, the flange 4, which may be termed the base flange, is marked off into six equal parts, and at the lines of separation between such parts the flange is notched, as indicated at 5, and its ends are trimmed to an angle corresponding to the inclination of the sides of the notches 5. In the production of a six sided member, the notches 5 embrace 60°, and by bending the flange 3 adjacent the apex of each of the notches 5 until the sides of said notches are brought together, a perfect hexagonal figure is produced. The above steps are present in the making of each of the members 1 and 2, but prior to the bending of the flange 3 of the top member, the inner edge portions of the parts of the base flange 4 between the notches 5 are bent downwardly on the line a—a of Fig. 6 thereby to produce the flanges designated 6 in Figs. 1 and 3. The base and upright flanges of the bottom member 2 are designated, respectively, 7 and 8. Where the edges of the notches 5 are brought together, and where the ends of the strip are engaged with each other, the joints are secured by deposits of solder or like material, as indicated at 10. The solder deposits on the lower member 2 are designated 11.

The corresponding corners of the flanges 6 and 8 of the respective members 1 and 2 are connected together by angular uprights 12, and these uprights are tied together intermediate their ends by ornamental cross members 13. Panes 14 of glass of any desired color and surface treatment are set within the panels defined by the flanges 6 and 8 and the uprights 12 and they are held in place in accordance with common practice by metal tongues 15 that are secured, as by soldering, 105 to the member 1 and uprights 12.

The fixtures illustrated in plan in Figs. 7, 8 and 9 are identical in structural respects with the one above described, the parts being 110 designated by the same reference characters

as are used to indicate the corresponding elements of the former hexagonal device and the blanks from which their respective top members are made are illustrated in Figs. 7^a to 9^a respectively.

It is apparent from the foregoing description that my invention provides a very substantial construction, and one that is accurate of outline and neat of appearance; and by the 10 method provided by the invention the manufacture of the lantern frame, in various polygonal shapes, is greatly expedited and cheapened over prevailing methods.

Having thus described my invention, what 15 I claim is:—

1. In a fixture frame of the class set forth, an open frame-like polygonal member consisting of a base flange made up of a plurality of parts arranged in endwise abutting relation 20 and an upstanding peripheral flange and a flange depending from the inner edge of the base flange, sections of the peripheral flange being integral with and common to at least two parts of the base flange and connecting 25 said parts together in the aforesaid abutting relation, a second similarly shaped frame member spaced below the former member, and uprights connecting the corresponding corners of the frame members.
- 30 2. In a fixture frame of the class set forth, a top polygonal member, a bottom open frame-like polygonal member consisting of a base flange made up of a plurality of parts arranged in endwise abutting relation and an

upstanding peripheral flange, sections of the 35 peripheral flange being integral with and common to at least two parts of the base flange and connecting said parts together in the aforesaid abutting relation, and uprights connecting the corresponding corners of the 40 top and bottom members.

3. In a fixture frame of the class set forth, a one-piece open frame-like polygonal member having an upstanding peripheral flange and a flange depending from its inner edge, 45 said member inwardly of its peripheral flange being notched at points spaced apart about the member and having the opposed edges of the notches in abutting relation, a second similarly shaped frame member spaced below 50 the former member, and uprights connecting the corners of the second frame member to the corresponding corners of the depending flange of the first mentioned member.

4. In a fixture frame of the class set forth, 55 a top polygonal member, a bottom open frame-like polygonal member having an upstanding peripheral flange, said member being notched inwardly of said flange at points spaced apart throughout its length 60 and the opposed edges of the notches being in abutting relation, and uprights connecting the corners of the peripheral flange of the bottom member to the corresponding corners of the top member.

In testimony whereof, I hereunto affix my signature.

HARRY E. KADEN.
